FOLDABLE GOLF BAG CARRIAGE

John L. Stableford, London, England

Application October 11, 1949, Serial No. 120,728
In Great Britain October 22, 1948

11 Claims. (Cl. 280—41)

1

This invention concerns a new or improved golf bag carriage and has particular reference to the form of carriage in which a pair of wheels are carried by legs which can be folded to a stowed position alongside a golf bag mounted on the carriage or moved to a downwardly extended operative position in which they project transversely from the carriage and bag to support the latter above the ground, the carriage being furnished with a handle or drawbar by which it may be maneuvered with the bag more or less horizontally disposed, and the carriage being capable, when at rest with its legs extended, of serving as a stand for the bag and of holding the latter in an upwardly inclined position with its foot at or near ground level and with its head or mouth conveniently disposed for removing clubs from the bag and for reinserting them into the bag.

The object of this invention is to provide an improved golf bag carriage of the aforementioned form.

In order that the nature of the invention may be more readily understood and carried into practice, one embodiment of the same, and certain modifications of such embodiment, will now be described with reference to the accompanying drawings, in which:

Figure 1 is a perspective view of the golf bag carriage according to the said embodiment of the invention, the carriage being shown in its operative condition and the golf bag being indicated in dot and dash lines on the carriage;

Figure 2 is a view similar to Figure 1, showing a golf bag applied to the carriage and illustrating the latter in a collapsed or stowed condition;

Figure 3 is a rear elevation of one of the legs and the associated part of the crosspiece of the backbone of the carriage;

Figure 4 is a side elevation taken in the direction of arrow A, Figure 3;

Figure 5 is a side elevation taken in the direction of arrow B, Figure 3;

Figure 6 is an enlarged part sectional elevation on line VI—VI, Figure 4;

Figure 7 is a side elevation of the rear end of the carriage shown in Figures 1 and 2;

Figure 8 is a section on line VIII—VIII of Figure 1;

Figure 9 is a side elevation of the front end of the carriage shown in Figure 8;

Figure 10 is a sectional plan on the line X—X of Figure 9;

2

Figures 11 and 12 are respectively a rear elevation and part sectional plan of a modification of the wheel mountings shown in Figures 3 and 5; and

5 Figure 13 shows an alternate form of the wheel mounting.

Referring to Figures 1 to 10 of the drawings, it will be seen that the golf bag carriage there illustrated comprises a straight rigid backbone 1 which is conveniently formed of metal tube and along and above which the golf bag 2 is adapted to lie with the backbone 1 under the longitudinal centre line of the undersurface of the bag.

At one end the backbone 1 is furnished with 15 an L-shaped foot 3, the upturned limb 4 of which is adapted to engage against the bottom 5 of the bag 2 to prevent the latter sliding down the backbone 1.

To the foot 3 is fixed a transversely arranged 20 U-shaped bracket 6 adapted to receive within it the foot end of the bag so as to position the latter centrally in a transverse direction with respect to the backbone 1, the U-shaped bracket 6 being furnished with an adjustable strap 7 adapted to embrace the foot end of the bag to hold the latter upon the backbone 1.

A U-shaped bracket 8, similar to the bracket 6, is provided for holding and positioning the neck or mouth end of the bag 2 upon the backbone, the bracket 8 being furnished with an adjustable strap 9 similar to the strap 7 and being carried upon a head bracket 10 which is conveniently in the form of a metal casting fixed at one end upon the front end of the backbone 1 and projecting laterally from the backbone 1 at right angles thereto as clearly shown in Figures 1, 8 and 10 of the drawings.

In the outer end of the head bracket 10 fixed to the backbone 1 is adjustably mounted, in a 40 telescopic fashion, an adjustable and stowable handle by which the carriage may be towed or otherwise maneuvered, this handle conveniently being formed of metal tube and having a crooked front end 12. The stem 11 of the said handle lies alongside the backbone 1 in parallelism therewith but is offset laterally from the backbone so that the handle does not obstruct the mouth of the bag 2 and render difficult the withdrawal of clubs from, or the replacement of clubs 45 into, the bag.

The stem 11 of the said handle is axially adjustable in the head bracket 10, being housed in a transverse bore in this bracket which is furnished with a longitudinally split boss 13 at one 55 end, such boss having a pair of lugs 14, 15 ar-

ranged one on either side of the split in the boss and being adapted to be drawn together by means of a knurled nut 16 on the screw-threaded end of a bolt or stud 17 anchored to the lug 14 and passing freely through the lug 15. Thus the nut 16 may be released and the stem 11 of the said handle axially adjusted in the head bracket 10 to any desired position such as, for example, the extended position shown in full lines in Figure 1 or the stowed position shown in dotted lines at 18 in Figure 1 and the full line position shown in Figure 2. Also the handle may be turned about the longitudinal axis of its stem 11 so that its crooked end 12 projects upwardly as shown in Figure 1 or occupies an inverted position in which the crook lies below the stem of the handle instead of above it, as shown. The crook could, of course, be adjusted to any other position about the axis of the stem 11 of the handle.

To lock the said handle against rotation in the head bracket 10 when extended, the inner end of the handle is provided with a cross pin 19 (Figure 1) which, when the handle is pulled outwardly to its maximum extent, engages in diametrically opposite grooves 20 (Figure 10) in the rear end face of the boss 13 of the head bracket 10. It will be obvious that, when the handle has been pulled out to this extended position and the nut 16 has been tightened up, the handle will be locked both against axial movement in the head bracket 10 and also against rotational movement in this head.

If desired, another cross pin 21, indicated in dotted lines in Figure 10 and similar to the cross-pin 19 above described, may be provided near the crooked end 12 of the handle for engagement with grooves (similar to the grooves 20) correspondingly provided in the front end face of the head bracket 10 to prevent the handle rotating about the axis of its stem when the handle is pushed to its rearmost or stowed position.

Between the front and rear ends of the backbone 1, and rather nearer the rear end than the front end thereof, the backbone is provided with a crosspiece 22 (Figures 1, 3 and 6) which projects laterally perpendicularly from the backbone equally on each side thereof. This crosspiece is conveniently in the form of a metal casting (which may be hollowed for lightness) which has its upper surface 23 recessed to form a saddle or cradle to receive the lower portion of the bag 2 to assist in positioning the latter on the carriage.

To each end of the said crosspiece is independently pivoted the upper end of a leg conveniently formed of metal tube, there being thus two legs which are marked in the drawings respectively 24 and 25. At its lower end each of the legs 24 and 25 carries a tired wheel; as these wheels are identical in form they are both marked with the same reference numeral, namely 26. The legs and wheels and the method of mounting these parts will subsequently be more fully explained.

At each end of the crosspiece 22 is a bracket 27, each bracket being of U-shape in plan and quadrant shape in side elevation and each comprising two parallel side sector-shaped plates or cheeks 28. The brackets 27 may be formed integrally with the crosspiece 22 or be attached thereto and the longitudinal upper edges of each of the brackets 27 are parallel to one another and to the corresponding edges of the other bracket 27 and also to the longitudinal axis of the backbone 1. The rear ends 45 of the brackets 27 are flush with the rear surface of the crosspiece 22 but the brackets project forwardly beyond the front surface of the

crosspiece. Also the rear ends 45 of the brackets 27 are recessed at their upper ends at 29 as shown in Figures 1, 2, 3, 4 and 6.

The brackets 27 are arranged symmetrically one on either side of the longitudinal vertical medial plane of the backbone 1, this plane being indicated in Figure 6 by a dash and dot line 30, and both cheeks 28 of both brackets 27 lie in planes which diverge downwardly and outwardly with respect to the plane 30 as is quite clear from Figure 6.

Each of the legs 24 and 25 of the carriage has a straight upper portion 31 which is located between the pair of cheeks 28 of its particular bracket 27, the upper part of the straight portion 31 of each leg being pivoted to its end of the crosspiece 22 and its bracket 27 by means of a pivot stud 32 passing through the upper rear corner of the bracket 27, diametrically through the leg, and screwing into the crosspiece 22 (see Figure 6) and either being riveted over to prevent accidental removal from the crosspiece or being furnished with a nut (not shown).

The axis 33 of each pivot stud 32 is disposed in a transverse plane perpendicularly penetrated by the longitudinal axis of the backbone 1 of the carriage. Moreover each pivot stud axis 33 is at right angles to the planes of the cheeks 28 of the bracket 27 through which the pivot stud passes and also inclines, in the said transverse plane, upwardly and outwardly from the backbone 1 as is clearly shown in Figure 6, the plane of the drawing representing the said transverse plane. The axes 33 are arranged symmetrically one on either side of, and above, the backbone 1 and preferably are both arranged in the same transverse plane although they could incline slightly forwardly and outwardly as well and upwardly and outwardly, if desired.

With the axes 33 of the studs 32 arranged as above described, as the legs 24 and 25 are moved from their stowed positions shown in Figure 2 to the extended operative positions shown in Figure 1, the legs swing in planes represented by the dot and dash lines 34 (Figure 6) which are symmetrically downwardly divergent from the said longitudinal vertical medial plane represented by the line 30 so that the lateral spacing of the wheels 26 increases as the legs move from their stowed towards their said operative positions. Thus when the legs are in the stowed position shown in Figure 2 the wheels are close to and lie alongside the bag 2 on the carriage, whilst when the legs are moved to their operative positions the wheels are disposed well below the golf bag 2 and are considerably spaced apart symmetrically on either side of the bag. One of the wheels 26 is shown in Figure 3 in full lines in its operative position but the stowed position of the wheel is also illustrated in dotted lines in this figure so that the marked inward movement of the wheel in passing from its extended to its stowed position is very well shown by this figure.

If the axes 33 are slightly inclined forwardly with respect to the transverse plane perpendicularly penetrated by the longitudinal axis of the backbone 1 (i. e. the plane in which Figure 6 is drawn) the inward and outward movement of the wheels 26 will be still further accentuated.

Conveniently in a carriage such as shown in the drawings, the pivoting axes 33 for the legs 24 and 25 each subtend an included angle α with the said longitudinal vertical medial plane 30 (see Figure 6) of $65\frac{1}{2}^\circ$ so that the axes 33 of the two

studs 32 subtend between them on their upper sides an angle of 131°, the axes 33 being symmetrical with respect to the plane 30.

As the upper portions 31 of the legs 24 and 25 are at right angles to the studs 32 and their axes 33, the longitudinal axes of these upper portions of the legs lie in the planes 34 hereinbefore referred to and subtend, when the legs are in their operative positions shown in Figures 1, 3 and 6, an angle β of 24½° with the said longitudinal medial plane 30 of the backbone 1 when the angle α is 65½°. Thus the upper portions 31 of the legs 24 and 25 splay downwardly and outwardly (symmetrically with respect to the longitudinal vertical medial plane 30 of the backbone 1) at an included angle of 49°.

The above angular dimensions are given for a preferred arrangement, but it will be understood that some deviation from these angles is possible without departing from the spirit of the invention. Nevertheless it is desirable that the angle α should lie between 60° and 70° and that the angle β should be between 30° and 20°.

The outward splaying of the legs has the effect of making the carriage very stable when the legs are extended and operative to support the carriage with a bag thereon and, in addition, has the effect of relieving the studs 32 of a proportion of the upward thrust resulting from the load on the legs, this upward thrust being partially transferred to the outer cheeks of the pairs of cheeks 28 of the two brackets 27 of the crosspiece 22, which cheeks also serve to resist the outward thrust of the legs of the carriage when these legs are extended. The inner cheeks of each pair of cheeks 28 of the brackets 27 absorb inward thrust applied to the legs 24 and 25.

One or both of the cheeks 28 of each of the U-shaped brackets 27 forms a quadrant or gate for co-operation with a catch for locking the associated leg respectively in its operative and stowed positions. In the drawings both cheeks 28 of each bracket 27 function in this way, each being furnished at its arcuate edge with a pair of notches respectively marked 35 and 36. These notches are each of a rectangular form and are arranged one near each end of the arcuate edge of their sector shaped cheek 28 for selective co-operation with the ends 37 of a catch bar 38 projecting radially outwardly, at diametrically opposite positions, from the corresponding tubular leg of the carriage.

As will be seen clearly from Figure 6, the catch bar 38 passes diametrically through the upper part 31 of its carriage leg at right angles to the longitudinal axis thereof, the leg being furnished with a longitudinally extending diametrical slot 39 permitting the catch bar 38 to move upwardly and downwardly in the leg for the engagement and disengagement of its ends 37 with and from the notches 36 or 35 in the adjacent cheeks 28.

Each cross bar 38 is fixed in the lower end of a plunger 40 coaxially arranged within the upper straight portion 31 of the corresponding carriage leg and reciprocable in the latter, the plunger 40 having a bearing at each end on the inner surface of the leg and normally being urged upwardly, to bring the catches 37 into their operative positions at the upper end of the slot 39 in the leg, by means of a compression spring 41 housed in an axial bore 42 in the upper end of the plunger 40 and bearing at its inner end upon the stud 32 forming the leg pivot and which passes perpendicularly through the upper end of the leg and through a longitudinal slot 43 in the plunger

40 within the leg, this slot being of a length sufficient to permit the plunger 40 to be depressed by the application of finger or thumb pressure to its upper end 44 to release the catches 37 from the locking engagement with the cheeks 28 in order to free the leg for movement about its pivot stud 32. The upper or outer end of the spring 41 bears against a grub screw 45' screwed into the upper end of the bore 42 of the plunger 40 and enabling the pressure exerted by the spring 41 to be adjusted.

When a leg is in its operative position, the catches 37 engage with notches 36 in the adjacent cheeks 28 of the bracket 27 and the rear surface of the leg bears against the rear wall 45 of the bracket 27, thus relieving the stud 32 and the catches 37 of a substantial percentage of the rearward thrust applied to the leg by the forward movement of the carriage. When the leg is in its stowed position, the catches 37 engage with the notches 35 in the cheeks 28 and in order to ensure registration of the catches 37 with these notches 35 when the leg is moved to the stowed position, a cross bar 46 is provided between the pair of cheeks 28 and against the inner surface of which the leg engages when it reaches its stowed position. These cross bars also serve to brace the cheeks 28.

Thus the catches 37 serve the double function of locking their leg alternatively in the stowed and extended position thereof.

As the upper part 31 of each of the legs 24 and 25 is embraced between a pair of the said cheeks 28 of a U-shaped bracket 27 at all times, it will be apparent that the movement of the leg from its stowed position to its extended position and vice versa is guided at all times.

Each of the legs 24 and 25 preferably has its intermediate portion 47 (see Figure 3) joggled 40 outwardly away from its straight pivoted upper portion 31, the lower portion 48 of each leg being rather nearer to the vertical than the upper portion 31 of the leg (speaking of the latter in the position shown in Figure 3) whereby the wheel carried by the lower part of the leg is disposed in a plane only a little off the vertical.

Moreover in their stowed positions the legs of the carriage and their wheels lie closely alongside the backbone of the carriage with the straight upper parts of the legs substantially parallel to the said backbone but, as the legs are swung to their extended and operative positions, their wheel-carrying ends separate laterally of the backbone of the carriage so that the legs diverge downwardly from the said backbone and with respect to one another, whereby the wheels are more widely spaced with respect to one another when the legs are in their operative positions than they are when the legs are in their stowed positions.

Each of the wheels 26 of the carriage is mounted on a stub axle 49 (see Figures 3 and 5 in particular) secured to one end of a flat lever 50 passing through a diametrical slot 51 in the lower end portion 48 of the associated leg 24 or 25, the lever 50 being pivoted to the leg upon a bolt 52 passing diametrically through the leg at right angles to the plane of the lever 50 and the said slot 51. The lever 50 is adapted to swing about the bolt 52 in a plane containing the longitudinal axis of the lower part 48 of the corresponding leg and at right angles to the axis of the bolt 52, and the bolt 52 is located between the ends of the lever 50 (which projects forwardly and rearwardly beyond its leg) nearer the rear end

53 of the lever than the front end thereof where the stub axle 49 is carried.

A tension spring 54 is anchored at its lower end to the rear end 53 of the lever 50 and is anchored at its upper end to a screw 55 secured in the carriage leg, the latter being provided with two or more spaced screw threaded holes 56 adapted selectively to receive the screw 55 so that the tension on the spring 54 can be modified according to requirements. Thus each wheel 26 of the carriage is independently resiliently or spring mounted on its leg and the arrangement of the pivot 52 of the lever 50 for each wheel, and the positioning and setting of the spring 54 are such that the wheel leverage progressively increases as the wheel is subjected to load, the springing thus being at first relatively light but progressively increasing in its resistance to the deflection of the wheel in an upward direction.

Rubber or other resilient buffers or cushions 57 are mounted one in the lower end of each of the carriage legs, these buffers or cushions serving as silencers and dampers for the wheel carrying levers 50 against the under edges of which the buffers or cushions are adapted to engage as the wheels are moved upwardly with respect to their legs. The buffers or cushions 57 are conveniently in the form of rubber or like resilient plugs inserted tightly into the lower ends of the legs and retained in that position by friction or by positive means, such as an adhesive or a cross pin, as indicated by dotted lines at 58 (Figure 5), if desired.

The rear end of the backbone 1 of the carriage may be furnished with a tail wheel 59 (Figures 1, 2 and 7) mounted on a horizontal spindle 60 carried in an inverted U-shaped bracket 61 fixed to the underside of the L-shaped foot 3 with a spindle at right angles to, but below, the backbone 1. This tail wheel may be formed of any suitable material but is preferably formed of a resilient substance such as, for example, rubber or is provided with a tire of such resilient material. The tail wheel 59 gives the carriage, with the wheels 26, a three-point suspension when the legs 24 and 25 are extended and enables the carriage to be traversed over the ground quite easily even when the carriage is merely acting as a stand for the bag, the latter being supported in the usual oblique position in which clubs are removed from, or replaced into, the bag. More particularly however the tail wheel facilitates the movement of the carriage (with the bag thereon) along a railway platform, a pavement, a path, road or the like whilst the main wheels 26 are still stowed; consequently the tail wheel very considerably further facilitates the transport of the bag between the home and the golf course and in like circumstances.

If desired the tail wheel may be resiliently mounted on the backbone 1.

In order to bring the plane of the rim of each wheel 26 inwardly nearer to the lower end 48 of the associated carriage leg, and to avoid the necessity for providing the diametrical slot 51 in the lower part of the leg and any danger of the lever rubbing the sides of such slot and creating a squeak or rattle, the modified mounting of the wheel shown in Figures 11 and 12 may be adopted. As will be seen from these figures the pivot 52' for the wheel carrying lever 50' is carried by a lug 62 fixed to the lower end of the corresponding leg 24 or 25 of the carriage and the front part of the lever 50' is joggled in-

wardly so as to bring the stub axle 49' of the wheel 26 inwardly slightly so that the rim of this wheel is closer to the lower part 48 of the leg than is the case in the arrangement shown in Figure 3, for example.

5 A still further modified wheel mounting is shown in Figure 13. In this arrangement the wheel carrying lever 50'' is carried upon a spindle 52'' bonded coaxially to the inner surface of a rubber or other suitable resilient sleeve 63 having its outer surface bonded to the internal surface of a cylinder 64 concentric with the spindle 52'' and secured to the lower extremity of the leg 24 or 25 of the carriage with its axis perpendicular to such lower part of the leg, this arrangement providing a resilient mounting of the "silent bloc" or like rubber to metal type for the said wheel carrying lever 50''.

I claim:

20 1. A golf bag carriage comprising a backbone adapted to support a golf bag therealong; a handle for maneuvering the carriage; a pair of similar independent legs; a wheel at the lower part of each of said legs; a pivot on the said backbone for the upper part of each of the said legs; said pivots forming the sole connection between the said legs and the said backbone and being arranged transversely of the longitudinal vertical medial plane of the latter and so as to incline symmetrically upwardly and outwardly from such backbone and each leg being adapted to swing independently of the other leg and about its own pivot from a stowed position in which the leg lies alongside the said backbone to an operative position in which it projects transversely downwardly from such backbone, and vice-versa; and independent spring catch means on each of said legs adjacent the pivoted end thereof for engagement with co-operating notched means on said backbone for locking the leg to said backbone releasably to retain the leg alternatively in either its operative or its stowed position.

45 2. A golf bag carriage comprising a backbone adapted to support a golf bag therealong; a handle for maneuvering the carriage and laterally offset from said backbone; a pair of similar independent legs each having its lower part outwardly cranked from its upper part; a wheel at the lower part of each of said legs; a pivot on the said backbone for the upper part of each of the said legs; said pivots forming the sole connection of said legs to the said backbone and being arranged transversely of the longitudinal vertical medial plane of the such backbone and so as to incline symmetrically upwardly and outwardly from the latter and each leg being adapted to swing independently of the other leg about its own pivot from a stowed position in which the leg lies alongside the said backbone to an operative position in which it projects transversely downwardly from such backbone, and vice versa; and guide means carried by said backbone for slidably engaging said legs on their outer sides as they swing to and from their stowed positions and for resisting outward lateral thrusts applied to the said legs, and catch means on said legs adapted for co-operation with the said guide means to lock the legs alternatively in their operative and stowed positions.

60 3. A golf bag carriage comprising a backbone adapted to support a golf bag therealong; a handle for maneuvering the carriage and laterally offset from the said backbone; a pair of similar independent legs; a wheel at the lower part of

each of said legs; a pivot on the said backbone for the upper part of each of the said legs; said pivots being arranged transversely of the longitudinal vertical medial plane of the said backbone and so as to incline symmetrically upwardly and outwardly from such backbone and each leg being adapted to swing independently of the other leg and about its own pivot from a stowed position in which the leg lies alongside the said backbone to an operative position in which it projects transversely downwardly from such backbone, and vice versa; a pair of guide cheeks for each of said legs, such pairs of guide cheeks being rigidly carried by the said backbone and each pair being adapted to embrace the upper part of one of said legs between them to guide the leg in its swinging movement from the stowed to the operative position and to absorb lateral thrusts applied to the leg; a bearing surface at the rear ends of each of the said pairs of guide cheeks against which the upper part of the corresponding leg engages when in its operative position; and independent catch means on each of said legs adjacent the pivoted end thereof for releasably locking the leg to its guide cheek in either of two alternative positions, namely a stowed position and an operative position.

4. A golf bag carriage comprising a backbone adapted to support a golf bag therealong; a handle on the said backbone for manoeuvring the carriage; a pair of similar independent legs; a wheel at the lower part of each of said legs; a pivot on the said backbone for the upper part of each of the said legs; said pivots being arranged transversely of the longitudinal vertical medial plane of the said backbone and so as to incline symmetrically upwardly and outwardly from such backbone and each leg being adapted to swing independently of the other leg and about its own pivot from a stowed position in which the leg lies alongside the said backbone to an operative position in which it projects transversely downwardly from such backbone, and vice versa; a pair of guide cheeks for each of said legs, such pairs of guide cheeks being rigidly carried by the said backbone and each pair being adapted to embrace the upper part of one of said legs between them to guide the leg in its swinging movement from the stowed to the operative position and to absorb lateral thrusts applied to the leg; a spring catch on the upper part of each of the said legs adapted selectively to engage in at least one of the said adjacent guide cheeks for releasably locking its leg to the said backbone in either of two alternative positions, namely a stowed position and an operative position; and manually operable means on each of said legs for releasing the spring catch of such leg from engagement with the said guide cheek to release the leg for swinging movement about its pivot.

5. A golf bag carriage comprising a backbone adapted to support a golf bag therealong; a handle on the said backbone for manoeuvring the carriage; a pair of similar independent legs; a pivot on the said backbone for the upper part of each of the said legs; said pivots forming the sole connection of the said legs to the said backbone and being arranged transversely of the longitudinal vertical medial plane of the said backbone and so as to incline symmetrically upwardly and outwardly from the latter and each leg being adapted to swing independently of the other leg and about its own pivot from a stowed position in which the leg lies alongside the said backbone to an operative position in which it projects

transversely downwardly from such backbone, and vice versa; a wheel resiliently mounted on the lower part of each of said legs; and independent sliding catch means on each of said legs adjacent the pivoted end thereof for releasably locking the leg independently of the other leg to the said backbone in either of two alternative positions, namely a stowed position and an operative position.

10. A golf bag carriage comprising a backbone adapted to support a golf bag therealong; a longitudinally and rotationally adjustable handle on the said backbone for manoeuvring the carriage; a pair of similar independent legs; a pivot on the said backbone for the upper part of each of the said legs; said pivots forming the sole connection of the said legs to the said backbone and being arranged transversely of the longitudinal vertical medial plane of the backbone and so as to incline symmetrically upwardly and outwardly from the same and each said leg being adapted to swing independently of the other leg and about its own pivot from a stowed position in which the leg lies alongside the said backbone to an operative position in which it projects transversely downwardly from such backbone, and vice versa; a wheel on the lower end of each of said legs; a pair of guide cheeks for each of said legs, such pairs of guide cheeks being rigidly carried by the said backbone and each pair being adapted to embrace the upper part of one of said legs between them to guide the leg in its swinging movement from the stowed to the operative position and to absorb lateral thrusts applied to the leg; a spring catch on the upper part of each of the said legs adapted selectively to engage in at least one of the said adjacent guide cheeks for releasably locking its leg to the said backbone in either of two alternative positions, namely a stowed position and an operative position; and manually operable means on each of said legs for releasing the spring catch of such leg from engagement with the said guide cheek to release the leg for swinging movement about its pivot.

7. A golf bag carriage comprising a backbone adapted to support a golf bag therealong; a handle stowably attached to said backbone and adapted for manoeuvring the carriage; a cross-piece on said backbone and spaced from the ends thereof; a pair of similar independent legs; a wheel at the lower part of each of said legs; a pivot for the upper part of each of the said legs; said pivots being carried one at each end of the said crosspiece and being arranged transversely of the longitudinal vertical medial plane of the said backbone and so as to incline symmetrically upwardly and outwardly from such backbone; each of said legs being adapted to swing independently of the other leg and about its own pivot from a stowed position in which the leg lies alongside the said backbone to an operative position in which it projects transversely downwardly from such backbone, and vice versa; a pair of guide cheeks for each of said legs, such pairs of guide cheeks being rigidly carried by the said crosspiece and each pair being adapted to embrace the upper part of one of said legs between them to guide the leg in its swinging movement from the stowed to the operative position and to absorb lateral thrusts applied to the leg; a spring catch on the upper part of each of the said legs adapted selectively to engage in at least one of the said adjacent guide cheeks for releasably locking its leg to the said backbone in either of two alternative positions, namely a stowed

11

position and an operative position; and manually operable means on each of said legs for releasing the spring catch of such leg from engagement with the said guide cheek to release the leg for swinging movement about its pivot.

8. A golf bag carriage comprising a backbone adapted to support a golf bag therealong; means for retaining a golf bag on said backbone; a handle stowably attached to said backbone and adapted for manoeuvring the carriage; a crosspiece on said backbone and spaced from the ends thereof; a pivot for the upper part of each of the said legs; said pivots forming the sole connection between the said legs and the said backbone and being carried one at each end of the said crosspiece and arranged transversely of the longitudinal vertical medial plane of the same and also so as to incline symmetrically upwardly and outwardly from such backbone, each of said legs being adapted to swing independently of the other leg and about its own pivot from a stowed position in which the leg lies alongside the said backbone to an operative position in which it projects transversely downwardly from such backbone divergently with respect to the other such leg, and vice versa; a wheel carried by the lower part of each of said legs; a pair of guide cheeks for each of said legs, such pairs of guide cheeks being rigidly carried by the said crosspiece and each pair being adapted to embrace the upper part of one of said legs between them to guide the leg in its swinging movement from the stowed to the operative position; a spring catch on the upper part of each of the said legs adapted selectively to engage in at least one of the said adjacent guide cheeks for releasably locking its leg to the said backbone in either of two alternative positions, namely a stowed position and an operative position; and manually operable means on each of said legs for releasing the spring catch of such leg from engagement with the said guide cheek to release the leg for swinging movement about its pivot.

9. A golf bag carriage comprising a backbone adapted to support a golf bag therealong; a handle mounted at the front end of the said backbone to one side thereof and adapted for endwise sliding adjustment to either an extended or stowed position at will; means for locking said handle alternatively in one or the other of its two positions; a tail wheel at the rear end of the said backbone; a crosspiece on said backbone and spaced from the ends thereof; a pair of similar independent legs; a wheel resiliently mounted on the lower end of each of said legs; a pivot for the upper part of each of the said legs; said pivots being carried one at each end of the said crosspiece and being arranged transversely of the longitudinal vertical medial plane of the said backbone and so as to incline symmetrically upwardly and outwardly from such backbone, each of said legs being adapted to swing independently of the other leg and about its own pivot from a stowed position in which the leg lies alongside the said backbone to an operative position in which it projects transversely downwardly from such backbone, and vice versa; whereby the said wheels are more widely spaced when the legs are in their operative positions than when the legs are in their stowed positions; means at the ends of said crosspiece for embracing and guiding, and for absorbing some of the lateral thrusts applied to the upper parts of said legs; and independent catch means for each of said legs adjacent the pivoted end thereof for

12

releasably locking the leg to the said crosspiece in either of two alternative positions, namely a stowed position and an operative position.

10. A golf bag carriage comprising a backbone adapted to support a golf bag therealong; a handle adapted to serve for manoeuvring the carriage and attached to said backbone so as to be slideable in the direction of the length of the latter for stowing or extension; means for locking the said handle with respect to the said backbone; a crosspiece on said backbone and spaced from the ends thereof; a pair of independent legs each having a straight upper part; a pivot for the said straight upper part of each of the said legs and at right angles to the axis of said straight upper part, said pivots being carried one at each end of the said crosspiece and being arranged transversely of the longitudinal vertical medial plane of the said backbone and so as to incline symmetrically upwardly and outwardly from said backbone at an acute angle of between 60 to 70° to said medial plane; each of said legs being adapted to swing independently of the other leg about its own pivot from a stowed position in which the leg lies alongside the said backbone to an operative position in which it projects transversely downwardly and outwardly from such backbone; a wheel supported at the lower end of each of said legs; a pair of guide cheeks for each of said legs, said pairs of guide cheeks being rigidly carried by the ends of said crosspiece and each pair being adapted to embrace between them the upper straight part of one of said legs to guide the leg in its swinging movement from the stowed to the operative position and vice versa and also to absorb lateral thrusts applied to the leg; and co-operating catch means on the said legs and cheeks for selectively locking the latter either in their stowed or their operative positions.

11. A golf bag carriage comprising a backbone adapted to support a golf bag therealong; a crosspiece on said backbone and spaced from the ends thereof; a pair of independent legs each having a straight upper part; a pivot for the said straight upper part of each of the said legs and at right angles to the axis of said straight upper part, said pivots being carried one at each end of the said crosspiece and being arranged transversely of the longitudinal vertical medial plane of the said backbone and so as to incline symmetrically upwardly and outwardly from said backbone at an acute angle of between 60 to 70° to said medial plane; each of said legs being adapted to swing independently of the other leg about its own pivot from a stowed position in which the leg lies alongside the said backbone to an operative position in which it projects transversely downwardly and outwardly from such backbone; a wheel supported at the lower end of each of said legs; a pair of guide cheeks for each of said legs, said pairs of guide cheeks being rigidly carried by the ends of said crosspiece and each pair being adapted to embrace between them the upper straight part of one of said legs to guide the leg in its swinging movement from the stowed to the operative position and vice versa and also to absorb lateral thrusts applied to the leg; co-operating catch means on the said legs and cheeks for selectively locking the latter either in their stowed or their operative positions; a head member secured to the front end of the said backbone and extending laterally therefrom; a handle for manoeuvring the carriage and comprising a stem and a grip

13

portion, the said stem being axially slidable in said head member and parallel to the said backbone; and means for locking the said handle selectively in an extended, stowed or intermediate position and for setting the same in a predetermined rotational position about the axis of said stem whereby the said grip portion may be fixed in a desired plane.

JOHN L. STABLEFORD. 10
